UNITED STATES PATENT OFFICE.

WILLIAM B. RUGGLES, OF BAYONNE, NEW JERSEY.

DRIER.

1,105,927.

Specification of Letters Patent.

Patented Aug. 4, 1914.

Application filed June 11, 1909. Serial No. 501,454.

To all whom it may concern:

Be it known that I, WILLIAM B. RUGGLES, a citizen of the United States, residing at Bayonne, in the county of Hudson and State 5 of New Jersey, have invented certain new and useful Improvements in Driers, of which the following is a full, clear, and exact description, such as will enable others skilled in the art to which it appertains to 10 make and use the same.

This invention relates to driers and with regard to the more specific features to driers of that style comprising a horizontally disposed, rotatable drum through which a heating medium is adapted to flow.

One of the objects of this invention is to provide a drier of the above general style that will be practical, comparatively simple in construction and operation, and highly 20 efficient in use.

Another object of the invention is to provide a drier with the parts thereof so assembled and connected as to permit a ready contraction and expansion of the various parts 25 under varying degrees of temperature.

Another object of the invention is to provide within a horizontally disposed, rotatable drum improved means for preventing material, after the same is fed into the 30 drum, from spilling out the front end thereof.

Another object of the invention is to provide the rotatable drum of a drier with means at the rear end thereof to efficiently 35 and rapidly conduct the material after the same is dried to a point without the drum.

Other objects will be in part obvious and in part pointed out hereinafter.

The invention accordingly consists in the 40 features of construction, combinations of elements and arrangement of parts which will be exemplified in the construction herein-after set forth, and the scope of the application of which will be indicated in the following claims.

In the accompanying drawings, wherein is illustrated one of the various possible embodiments of my invention, Figure 1 illustrates a side elevation of a drying apparatus, 50 showing certain parts thereof broken away or in dotted lines for the sake of clearness; Fig. 2 is a plan view of the apparatus shown in Fig. 1; Fig. 3 is a vertical, sectional view of a portion of the same apparatus, showing the front end of the drum; Fig. 4 is an 55 end view of Fig. 3, the flue being removed

taken on the line α — α , Fig. 3; Fig. 5 is a transverse section taken on the line y — y , Fig. 1; Fig. 6 is an end elevation of the rear end of the drum; Fig. 7 is a vertical, sectional view of the rear of the drum; and Figs. 8, 9 and 10 are detail views of the discharge chute and support.

Referring now to these drawings in detail, wherein similar references refer to similar parts throughout the several views of the drawings, 1 represents a furnace of any suitable construction adapted to furnish the heating medium to the drier through a flue 2 projecting into one end of a drum 3. The 70 drum 3, which is of cylindrical form and slightly inclined with respect to the horizontal, is provided with a central longitudinal flue 4 through which the heating medium is conducted to the rear end of the drier-drum. The flue 4 is preferably provided with a slightly enlarged extension 5 fitting over and around the flue 2 from the source 75 of heat. A space is preferably provided between the walls of the flue 2 and the annular extension 5 to permit air to be drawn therethrough into the flue 4 with the heating medium to effect a more perfect combustion thereof as it passes through the drum. The partition 5 also prevents a short-circuiting 80 of the heating medium to the fan at the point of connection between the drum and the source of heat. A space is also provided between the end of the flue 2 and the annular ring 6 connecting the flue 4 with the 85 extension 5 to permit a contraction or expansion of the various parts under varying degrees of temperature.

The flue 4 having projecting vanes 4' for stirring the material falling thereon is supported from the inner walls of the drum 3 by means of suitable connecting links 7 which are also arranged and connected to permit a longitudinal or expanding movement of the parts. A link 7' is rigidly connected with both the drum and the center flue 4 so that the latter may expand in both directions by means of the flexible connections 7. The links 7' are each made in two angularly shaped sections which are associated or assembled in the manner illustrated in Fig. 1 of the drawings, the inner portions of the sections being parallel and the outer portions comprising branches longitudinally disposed relatively to the drum, and said branches and the inner portions of the links are rigidly connected to said drum 100 105 110

and said flue, respectively. By making said links 7' in sections, as described, they may be readily inserted in position between the drum and the flue before assembly, and 5 thereafter rigidly secured thereto in the position illustrated.

Around the interior of the front end of the drum are a plurality of inclined curved buckets or flights 8 Fig. 3, connected to an 10 annular ring 9, onto which the material falls as it is fed into the drum. These flights are of such shape and so disposed within the drum as to catch the material and carry it upwardly and around as the drum rotates, 15 so that when it falls it slides along the curved surfaces thereof and shoots well into the drum, thereby preventing the material from spilling out at the front end, so objectionable with many driers of this general 20 style.

The rear end of the drum is provided with an end plate 10 Figs. 6 and 7, having a central opening in which is mounted a discharge plate 11 of conical formation provided with a plurality of radially disposed 25 partitions 12 so that when the material falls onto this plate 11 it is carried out through the opening in the plate 10. On the inner surface of this plate 10 are provided a plurality of flights or buckets 13 of 30 Z-shaped cross-section adapted to scoop up the material collecting at the rear end of the discharge drum after the same is dried. By reference to these figures it will appear 35 obvious that as the material is carried up by these buckets and approaches the upper point in the path of travel, it slides out the end thereof onto the plate 11, striking the curved or conical surface, from whence it 40 shoots out the end of the drum. A door 10' in the plate 10 permits access to the interior of the drum to clean or repair the same.

Longitudinally disposed vanes 14 are placed about the inner wall of the drum to 45 stir up the material as it passes along.

A suitable discharge chute 15, Figs. 8, 9 and 10, may be placed adjacent plate 11 in front of the discharge opening, to catch the material as it is discharged from the drum 50 through a flaring ring 16, and convey the same to a conveyer if desired.

A plurality of annular rings are disposed about the outer wall of the drum, one of which 17 is provided with teeth meshing 55 with the teeth of a pinion 17' driven by a suitable motor 18, as shown in Figs. 1 and 2. The other rings 19 have plane surfaces co-acting with suitable supporting rollers 20 beneath the same and horizontally disposed 60 rollers 21 rotating about vertical pivots co-acting with the sides of the rings 19 to prevent longitudinal movement of the drum.

Surrounding the point of connection between the flue 2 and the drum 3 is a stationary hood 22 having legs 23 resting on

the foundation of the apparatus. This hood is provided at one side with a hopper 24 terminating in a curved chute within the drum, as shown clearly in Fig. 3, for directing the material to be dried onto the rotating flights or buckets 8. A plurality of openings are provided in the front wall of the hood having hinged doors 25, or the like, to permit access to the interior thereof for the purpose of assembling or repairing the 75 parts, and also removing any material that may have collected within the drum.

Connected with the upper part of the hood is a conduit 26 leading to a suction-fan 27 mounted at any convenient point, as on 80 top of the furnace 1. This fan is adapted to withdraw the moisture given off by the material as the same is dried, and also create a draft through the drum from the discharge opening to draw the heating medium 85 discharged at the rear end of the flue 4 back to the front end of the drum. Regulating means may be applied if desired, at any convenient point within the conduit for regulating the amount of draft there- 90 through.

An opening 28 is provided at the rear of the hood 22 above the drum to permit access to the conduit for cleaning or repairing the same.

The operation of the apparatus is in brief as follows: Assuming a fire to have been built within the furnace and the apparatus to have become well heated, the motor 18 is started to rotate the drum 3 and the suction-fan 27 connected therewith after which the material to be dried is fed into the hopper 24 at the side of the hood where it falls by gravity onto the flights or buckets 8 about the interior of the rotating drum. It 105 is carried around until it reaches approximately the highest point of its travel, whence it falls onto the heated flue 4, thence to the bottom of the drier, where the operation is repeated by means of the longitudinally extending vanes 14. Owing to the slight inclination of the drum the material will gradually be conveyed to the rear end thereof, where it is caught by the flights or buckets 13, carried around thereby and allowed to fall on the conical plate 11, from whence it is discharged to the exterior of the drum into the chute 15 if desired.

As many changes could be made in the above construction and many apparently 120 widely different embodiments of this invention could be made without departing from the scope thereof, it is intended that all matter contained in the above description or shown in the accompanying drawings shall 125 be interpreted as illustrative and not in a limiting sense.

It is also to be understood that the language used in the following claims is intended to cover all of the generic and spe- 130

cific features of the invention herein described and all statements of the scope of the invention, which, as a matter of language, might be said to fall therebetween.

5 Having described my invention, what I claim as new and desire to secure by Letters Patent is:

1. In an apparatus of the character described, in combination, a substantially horizontally disposed, rotatable drum, a source of heat having a flue projecting into said drum, a longitudinal flue within said drum rotatable therewith and having a portion thereof surrounding the flue from said

15 source of heat and a stationary hood surrounding the point of connection between the longitudinal flue and the flue from said source of heat.

2. In an apparatus of the character described, in combination, a rotatable drum, having a central discharge opening at one end, a source of heat, a longitudinal flue within said drum connected with said source of heat through which the heating medium

25 passes, means for directing the material to be dried into said drum, a plurality of buckets arranged about the interior of said drum at one end thereof adapted to catch the material and convey the same further 30 into the drum and means at the opposite end of said drum for ejecting the material after being dried, through the central part thereof.

3. In an apparatus of the character described, in combination, a drum, a source of heat, means for directing the material to be dried into said drum, a plurality of buckets about the interior of said drum adapted to catch the material and convey

40 the same further into the drum, and a plurality of flights or buckets arranged at the opposite end of said drum adapted to catch the material after the same is dried and discharge the same from said drum.

45 4. In an apparatus of the character described, in combination, a rotatable drum, a source of heat, a longitudinally disposed flue within said drum connected with said source of heat, a plate at the rear end of said drum, and a plurality of flights or buckets mounted on said plate adapted to catch the material after the same is dried and discharge the same from said drum.

50 5. In an apparatus of the character described, in combination, a horizontally disposed, rotatable drum, a source of heat, a longitudinally disposed flue within said drum connected with said source of heat, a plate at the rear end of said drum, and a plurality of flights or buckets mounted on said plate adapted to catch the material after the same is dried and discharge the same from said drum, said plate having an opening to permit access to the interior of

55 6. In an apparatus of the character described, in combination, a rotatable drum, a source of heat, a longitudinal flue within said drum connected with said source of heat, a plate at the rear end of said drum, a discharge plate mounted upon said plate, and a plurality of flights or buckets secured to said first mentioned plate adapted to discharge the material after the same is dried onto said second mentioned plate, 75 from whence it is discharged from said drum.

7. In an apparatus of the character described, in combination, a drum, a source of heat, means for conducting the heating medium through said drum, means for rotating said drum, means for admitting the material to be dried at one end thereof, a centrally disposed, conical plate at the opposite end of said drum, and means for directing the material after the same is dried onto said plate, whereby it is discharged 85 from said drum.

8. In an apparatus of the character described, in combination, a rotatable drum 90 having a central discharge opening at one end, a source of heat, a longitudinally disposed flue connected with said source of heat, means for admitting material to be dried to said drum between said flue and the 95 interior wall of said drum, said drum being inclined with respect to the horizontal to permit material to pass from one end to the other, means for discharging the material after the same is dried through the 100 opening in the central part of said drum, means for rotating said drum, and means for preventing a longitudinal movement thereof.

9. In an apparatus of the character described, in combination, a rotatable drum, a source of heat connected therewith, a stationary hood surrounding said connection, means passing through said hood for conveying the material to be dried into said 110 drum, and a plurality of buckets arranged about the interior of said drum on which the material falls from the conveying means and by which it is carried farther into the drum.

10. In an apparatus of the character described, in combination, a rotatable drum, a source of heat connected therewith, a hood surrounding the point of connection between said drum and said source of heat, means passing through said hood for conducting 120 the material to be dried into the drum, and means within the drum on which the material falls adapted to prevent the material from spilling at the front end of said drum.

11. In an apparatus of the character described, in combination, a horizontally disposed, rotatable drum, a source of heat, a hood surrounding the point of connection between said drum and said source of heat, and a curved chute projecting through said

- 4
1. In an apparatus of the character described, a hood adapted to direct the material to be dried into the drum.
2. In an apparatus of the character described, in combination, a horizontally disposed, rotatable drum, a source of heat, a hood surrounding the point of connection between said drum and said source of heat, a chute for directing the material to be dried into the drum, and a plurality of buckets on which said material falls adapted to carry the material upwardly from whence it falls farther into the drum.
3. In an apparatus of the character described, in combination, a drum, a source of heat, a flue connected with the source of heat and projecting into said drum, and a hood surrounding said drum and said flue at the point of connection, and so connected therewith as to permit a longitudinal expansion and contraction of said parts.
4. In an apparatus of the character described, in combination, a drum having a longitudinal flue, a source of heat, a flue connected therewith and connected with said first mentioned flue, and a hood surrounding said point of connection, the walls of said hood being generally vertical while the walls of said drum and flues being generally horizontal, said walls being so arranged as to permit a longitudinal contraction and expansion of the same under varying degrees of temperature.
5. In an apparatus of the character described, in combination, a substantially horizontally disposed, rotatable drum, a source of heat, means projecting into said drum and connecting said source of heat with the interior of said drum, a stationary hood surrounding the point of connection, and a plurality of openings in the front of said hood to permit access to the interior thereof.
6. In an apparatus of the character described, in combination, a substantially horizontally disposed, rotatable drum, a source of heat, fluid conducting means connected with the interior of said drum and said source of heat, a stationary hood surrounding said connection, means for directing the material to be dried through said hood into said drum, and a plurality of openings arranged adjacent the end of said drum provided with doors to permit access to the interior of said drum.
7. In an apparatus of the character described, in combination, a drum having a centrally disposed discharge opening at one end, a source of heat, a hood, means therein for directing the material to be dried into the other end of said drum, means for discharging the material after the same is dried through said substantially centrally disposed opening at the opposite end of said drum, and means for causing a current of air to pass through said drum in an opposite direction to that of the material to be dried to remove the moisture expelled from the material as the same is dried.
8. In an apparatus of the character described, in combination, a substantially horizontally disposed, rotatable drum having a substantially centrally disposed opening at one end, a source of heat connected therewith and adapted to direct a heating medium through said drum to the opposite end thereof, means for drawing said heating medium back to the front end of said drum and means adapted to discharge material through said opening.
9. In an apparatus of the character described, in combination, a substantially horizontally disposed rotatable drum having a substantially centrally disposed opening at its end, and having a longitudinal flue therein, a source of heat communicating with said flue through which the heating medium is adapted to pass, means for directing the material to be dried into said drum through which it passes to the opposite end from whence it is discharged, means for causing a current of air together with said heating medium to pass through said drum in a direction opposite to that in which the material is fed for removing the moisture given off by the material as the same is dried and means adapted to discharge material through said opening.
10. In an apparatus of the character described, in combination, a rotatable drum, a source of heat, means for conducting a heating medium through said drum, a hood surrounding the connection between said source of heat and said drum, a plurality of doors in the front of said hood to permit access thereto, and a door in the rear wall of said hood to permit access to the upper part thereof.
11. In an apparatus of the character described, in combination, a rotatable drum having a discharge opening, a source of heat, means in said drum and spaced therefrom constituting a flue for a heated current, means for feeding the material to be dried into one end of said drum, and means adapted to raise and discharge the material after the same has been dried, at the opposite end of and through the central part of said drum.
12. In an apparatus of the character described, in combination, a substantially horizontally disposed rotatable drum, a source of heat, a flue within said drum constituting a passageway for the heated current, means for directing the material to be dried into one end of said drum, a discharging plate projecting within said drum at the opposite end thereof, and means for carrying the material after the same is dried into operative relation with said plate.
13. In an apparatus of the character described, in combination, a horizontally dis-

posed rotatable drum, a source of heat, a flue within said drum constituting a passageway for the heating medium, means for directing the material to be dried into one end of said drum, a discharging plate at the opposite end thereof, and a means for carrying the material after the same is dried into operative relation with said plate.

24. In an apparatus of the character described, in combination, a substantially horizontally disposed rotatable drum having a discharge opening, a flue within said drum constituting a passageway for a heating current, means for directing the material to be dried into one end of said drum, means carried by the drum adapted to guide the material from the directing means farther into the drum, and means adapted to raise and discharge the material at the opposite end of and through the central part of said drum.

25. In an apparatus of the character described, in combination, a substantially horizontally disposed rotatable drum having a discharge opening, a flue within said drum constituting a passageway for a heating current, means for directing the material to be dried into one end of said drum, inclined buckets carried by the drum adapted to guide the material from the directing means farther into the drum, and means adapted to raise and discharge the material at the opposite end of and through the central part of said drum.

35. 26. In an apparatus of the character described, in combination, a substantially horizontally disposed rotatable drum having a discharge opening, a flue within said drum constituting a passageway for a heating current, links connecting said drum and flue, one of said links comprising a plurality of sections rigidly connected to said drum and flue, means for directing the material to be dried into one end of said drum, and means adapted to raise and discharge the material at the opposite end of and through the central part of said drum.

27. In an apparatus of the character described, in combination, a substantially horizontally disposed rotatable drum having an opening at its discharge end, a flue within said drum constituting a passageway for a heating current, means for directing the material to be dried into one end of said drum, a conical plate within the drum disposed to guide material through said opening, and means comprising Z-shaped buckets at the opposite end of said drum adapted to raise the material in the drum and discharge the same upon said conical plate.

28. In an apparatus of the character described, in combination, a substantially horizontally disposed rotatable drum, a flue

within said drum constituting a passageway for a heating current, links connecting said drum and flue, one of said links comprising a plurality of sections assembled to form longitudinally disposed branches at one end rigidly connected to said drum, the other end of said sections being rigidly connected to said flue, means for directing the material to be dried into one end of said drum, and inclined buckets carried by the drum adapted to guide the material from the directing means farther into the drum.

29. In an apparatus of the character described, in combination, a substantially horizontally disposed rotatable drum, a flue within said drum constituting a passageway for a heating current, links connecting said drum and flue, one of said links comprising a plurality of sections assembled to form longitudinally disposed branches at one end rigidly connected to said drum, the other end of said sections being rigidly connected to said flue, means for directing the material to be dried into one end of said drum, inclined buckets carried by the drum adapted to guide the material from the directing means farther into the drum, said drum having a central discharge opening in the opposite end, a conical plate within the drum disposed to guide material through said opening, and means adapted to raise the material in the drum and discharge the same upon said conical plate.

30. In an apparatus of the character described, in combination, a substantially horizontally disposed rotatable drum, a flue within said drum constituting a passageway for a heating current, links connecting said drum and flue, one of said links comprising a plurality of sections assembled to form longitudinally disposed branches at one end rigidly connected to said drum, the other end of said sections being rigidly connected to said flue, means for directing the material to be dried into one end of said drum, inclined buckets carried by the drum adapted to guide the material from the directing means farther into the drum, said drum having a central discharge opening in the opposite end, a conical plate within the drum disposed to guide material through said opening, and means comprising Z-shaped buckets at the opposite end of said drum adapted to raise the material in the drum and discharge the same upon said conical plate.

In testimony whereof I affix my signature, in presence of two witnesses.

WILLIAM B. RUGGLES.
